APPARATUS FOR APPLYING COVERS TO BOOKS

Albert L. Saunders, 155 Dryden Drive, San Antonio, Tex.

Filed Nov. 8, 1957, Ser. No. 695,451

1 Claim. (Cl. 11—4)

This invention relates to devices for covering books, 15 and more particularly to an improved device for supporting a book to be covered and for facilitating the forming of the cover to be placed thereon.

A main object of the invention is to provide a novel and improved apparatus for forming a book cover and for supporting a book while the cover is fitted thereto, the apparatus being simple in construction, being easy to use, and enabling a book to be covered with a minimum amount of effort and in a relatively short time.

A further object of the invention is to provide an improved apparatus for supporting a book while a cover is formed and applied thereto, the apparatus involving inexpensive components, being foldable to a compact size for transportation or storage, and enabling a book to be fitted with a cover in a very short period of time and with a considerably lesser amount of effort than is required in the ordinary method of forming a book cover by the use of scissors.

Further objects and advantages of the invention will become apparent from the following description and claims, and from the accompanying drawings, wherein:

Figure 1 is a perspective view showing an apparatus according to the present invention and illustrating the manner in which the apparatus is employed to cover a book, the book being shown in dotted view.

Figure 2 is a top plan view of a template member employed in conjunction with the apparatus of Figure 1 for forming the book cover.

Figure 3 is an elevational view of the template of Figure 2.

Figure 4 is an end view of the template of Figures 2 and 3.

Figure 5 is an enlarged vertical cross sectional view taken on the line 5—5 of Figure 1.

Figure 6 is a horizontal cross sectional view taken on line 6—6 of Figure 5.

Referring to the drawings, and more particularly to Figure 1, 11 generally designates a device for supporting a book to be covered on a sheet of paper or similar covering material, such as the sheet 12 shown in Figure 1, for shaping the sheet to define a book cover. The device 11 comprises a pair of rigid plate members 13, 13 of any suitable relatively thin rigid sheet material, such as plywood, or the like, said plate members being rectangular in shape and substantially identical in size. Designated at 14, 14 are respective rigid blade-like strips of metal which are secured to the adjacent margins of the plate members 13, 13, said margins being suitably recessed to receive the strips and to support the strips so that their marginal portions project inwardly over the edges of the members 13, 13, as is clearly shown in Figure 5. The strips 14 may be fastened to the plate-like members 13, 13 in any suitable manner, as by the use of a plurality of spaced rivets 15 passing through the strips 14 and the subjacent marginal portions of the members 13.

2

Designated at 16, 16 are respective coiled springs having the right angled end portions 17, 17 which are respectively received in the adjacent outside edge portions of the plate-like members 13, 13, in the manner shown in Figure 6, the inturned spring ends being preferably permanently secured in the members 13, 13 so as to define resilient connections between the plate-like members biasing said members to substantially coplanar positions and being formed and arranged to exert clamping force on an object wedged between the strips 14, 14. Thus, a sheet of paper 12 may be placed on the plate-like members 13, 13, in the manner shown in Figure 1, and a book, shown in dotted view at 20 may be disposed with its covers 21, 21 open and with its back located between the strips 14, 14, the back of the book and the portion of the paper 12 subjacent thereto being depressed below the plane of the strips 14, 14 so that the book back and the portion of the paper sheet 12 engaged therewith are clamped between the strips 14, 14 by the action of the connecting coiled springs 16, 16.

Designated at 22 is a spring clamping member formed with the respective parallel arms 23, 23 and the connecting spring loops 24, as shown in Figure 1. The lower ends of the arms 23, 23 are formed with the outwardly extending terminal portions 25, 25 which terminate in the right angled, horizontally extending end lugs 26, 26.

As shown in Figure 1, the spring clamping member 22 is used to engage the leaves of the book to hold same pressed together while the covers 21, 21 of the book are supported over the respective plate-like members 13, 13 in overlying relationship to the plate or sheet 12.

Designated at 27 is a rigid template member of any suitable material, such as metal, hard plastic, or other suitable material, said member 27 being formed with the beveled longitudinal edge 28 and with the inclined beveled end edges 29, 29, the edges 28 and 29 defining cutting blades, as will be presently explained.

In using the apparatus, the book is placed over the sheet of paper 12 in the position illustrated in Figure 40 1 with the book back and the portion of the paper sheet adjacent thereto clamped between the blade-like strips 14, 14. The cutting template 27 is then positioned adjacent the edges of the covers 21, 21 to serve as guides in tearing the paper sheet to define flaps to be folded over the margins of the book covers 21, 21 in forming the book cover. The member 27 thus serves as a means for suitably shaping the paper sheet 12 to define the required flaps for covering the cover boards 21, 21 of the book. The inclined ends 29, 29 of the template are 50 suitably shaped so that the required flaps may be formed at their ends to suitably overlie the corners of the book cover elements 21, 21.

As will be understood, the spring clamp member 22 holds the leaves 20 of the book in upstanding, closely 55 compressed condition and the arms 25, 25 serve as supports to maintain the leaves 20 vertical while the book cover elements 21, 21 are held horizontally in overlying relation to the sheet of paper 12 and the subjacent plate-like elements 13, 13.

The template member 27 is formed with a pair of upstanding studs 30, 30 which are engageable in a pair of apertures 31, 31 formed in one of the plate-like members 13 for storing the template 27 when the apparatus is not in use. Similarly, the opposite plate-like member 65 13 is formed with a pair of apertures 32, 32 for receiving the lug elements 26, 26 of the spring clamp 22, for storing said spring clamp when the apparatus is not being used. With the template 27 and the spring clamp 22 70 engaged respectively with the apertures 31, 31 and 32, 32, the plate-like members 13, 13 may be folded substantially parallel to each other and suitably secured in folded

positions, for example, by means of a suitable fastening band, whereby the apparatus assumes a relatively compact size for easy storage.

As above explained, the plate-like members 13, 13 may be formed of any suitable rigid material, for example, plywood, Masonite, or the like.

While a specific embodiment of an improved apparatus for use in forming a book cover and for supporting a book while being covered has been disclosed in the foregoing description, it will be understood that various modifications within the spirit of the invention may occur to those skilled in the art. Therefore, it is intended that no limitations be placed on the invention except as defined by the scope of the appended claim.

What is claimed is:

A device for supporting a book to be covered on a horizontal sheet of covering material for shaping the sheet to define a book cover comprising a pair of side-by-side horizontal, coplanar rigid plate members movable relative to each other, respective rigid blade-like strips

secured to the adjacent margins of the plate members and projecting towards each other beyond the edges of the plate members, said plate members being adapted to support the sheet of covering material with an open book vertically disposed thereon and to receive the book back therebetween with the covering material and book back depressed below said blade-like strips, and respective coiled springs yieldably connecting the adjacent edges of said plate members at their respective opposite end portions and being formed and arranged to urge the plate members horizontally inwardly towards each other and to cause said blade-like strip to exert clamping force horizontally and inwardly on the book back and the depressed portion of the covering material located between 10 said blade-like strips.
